AUTOMATIC MUSICAL INSTRUMENT.

1,409,496.

Specification of Letters Patent. Patented Mar. 14, 1922.

Application filed November 26, 1917, Serial No. 203,893. Renewed December 19, 1921. Serial No. 523,586.

To all whom it may concern:

Be it known that I, CHARLES F. STODDARD, a citizen of the United States of America, residing in the city of New York, in the county and State of New York, have invented an Improvement in Automatic Musical Instruments, of which the following is a specification.

This invention relates to automatic means for playing musical instruments, such as pianos, and pertains more particularly to means for governing and varying tone intensities.

Among other objects the invention provides means to vary the general range of expression changes, which may be preferably combined with automatic expression governing and regulating mechanism. Such expression governing and regulating mechanism may have, if desired, the three-fold capacity for producing incremental changes in playing intensities; for maintaining uniform any given playing intensity, whether one or many notes are simultaneously sounded; and for producing substantially continuous progressive changes in playing intensities. For this purpose the invention may be embodied in an apparatus which is very simple and reliable in operation.

For illustration, the accompanying drawings show one practicable embodiment of the invention employing suitable pneumatically governed devices in combination with a piano action; but as will appear to those skilled in the art, the invention is susceptible of embodiment in various constructions and organizations other than that particularly shown and described herein. It will appear likewise that it is not indispensable that all the features of the invention must be used conjointly, since their respective substantial advantages may accrue from their separate application in any practicable manner to a suitable instrument.

The single figure of the accompanying drawings in a diagrammatic representation of a typical piano action with operating and governing means exemplifying the application and utility of the invention.

Referring to the drawings a striker or player pneumatic 1 is provided having a sticker 2 to act upon a wippen 3 and thereby operate the usual piano action, as well understood in the art. A wind trunk 7

leads to a wind chest for the motor pneumatics each of which has a secondary valve 8 controlled by a primary valve 9 operated from a tracker board T through a duct 10 in the usual manner.

The wind trunk 7 communicates with a regulated wind chest 12. A high exhaust chest 14 arranged for communication with the chest 12 may be connected by a trunk 15 with any source of pneumatic exhaust, such as a diagrammatically shown feeder bellows 16, which may be of any practicable type.

In the illustrative apparatus of the drawings, the striker pneumatics 1 may be operated by the exhaust in the regulated exhaust chest 12. In order to vary the operation of the striker pneumatics, this regulated exhaust may be varied by subjecting it more or less to the influence of high exhaust in chest 14. For this specific purpose a port 30 controlled by a valve 31 is provided between the high exhaust chest 14 and the regulated exhaust chest 12.

The valve 31 may be operated by any suitable means, preferably by apparatus of the general character of that herein illustrated. In this specific apparatus the stem 32 of the valve 31 is connected to a movable board 33 of a bellows apparatus presently described; said board being hinged at 17. Such apparatus has a three-fold function for controlling the valve 31, it automatically produces incremental changes in playing intensities; it performs a regulating function, that is, it maintains any given playing intensity whether one or many notes be sounded; and it automatically produces continuously progressive changes in playing intensities for crescendo and diminuendo purposes.

It is preferable with such apparatus that the means for varying the general range of expression changes are combined, although it will be obvious that other apparatus, having any one or all of the capacities of the apparatus herein described, may be combined therewith to advantage. Following a brief description, in the sequence indicated, of the three capacities of the apparatus acting through the bellows board 33, the embodiment of the further means referred to will be described. As the description proceeds it will be obvious that the invention is not dependent upon the specific details of construction

or the specific mode of operation of the apparatus herein described.

Beneath the board 33 are three bellows 34, 35 and 36 which have their upper boards secured to the common movable board 33 and their lower boards secured to a fixed plate 18.

Another bellows 37 has its lower board secured to the movable board 33 and its upper board to a stationary plate 38. A 10 condition of partial exhaust is maintained at all times in the bellows 37 as presently described. The degree of exhaust in bellows 37 may be varied, but for the present this function may be disregarded and the pressure 15 within the bellows acting upon the board 33 may be considered uniform. Thus, the pressure in the bellows 37, being always less than atmospheric pressure, said bellows in effect exerts continuously a uniform upward 20 pull on the board 33 contributing to control the valve 31.

Ducts 40, 41 and 42 enter respectively the bellows 34, 35 and 36. Each duct may be controlled by any practicable valve mechanism 25 to admit to its bellows either atmospheric pressure, or regulated pressure from the chest 12; and regulated pressure may be admitted to the bellows selectively, while atmospheric pressure will be present in those 30 bellows, if any, which do not contain regulated pressure. Whenever regulated pressure is present in any one or more of the bellows 34, 35 and 36 the effect thereof is to produce a downward pull upon the board 33. This downward pull is opposed by the 35 upward pull which results from the condition of partial exhaust in the bellows 37, the two contributing to control the valve 31. High exhaust in the chest 14 exerts some 40 downward pressure upon the area of the valve 31 itself; and regulated pressure in the chest 12 exerts some upward pressure upon the area of the valve. Since regulated pressure is usually greater, it generally 45 predominates and the resultant upon the valve itself is an upward pressure which combines with the resultant of the pressure in the several bellows to complete the control of the valve 31.

50 The construction and arrangement of the apparatus may be such that the opposed upward and downward acting forces control the valve and tend to hold it in a balanced condition. For example, if regulated pressure 55 be present in all three of the bellows 34, 35 and 36, the downward pull of these bellows upon the board 33 is at its maximum and tends to close the valve 31 and minimize the opening between the chests 12 and 14.

60 Under these circumstances, playing intensities, as controlled by this portion of apparatus, will be at the minimum. The bellows 34, 35 and 36 will then operate substantially as a single regulator pneumatic for maintaining 65 a uniform degree of exhaust in the

regulated pressure chest whether one or many notes are concurrently sounded. A substantial uniformity of playing intensities will thereby be maintained.

The bellows 34, 35 and 36 may be governed 70 to vary playing intensities by varying the downward acting force which they contribute to the control of the valve 31. If atmosphere be admitted to the bellows, 36 for example, the aggregate downward pull 75 on the board 33 is relaxed to some extent. To restore the condition of balance the degree of regulated exhaust acting upon the board 33 through bellows 34 and 35 will be permitted to increase. Therefore the apparatus 80 will operate to regulate playing intensities at a higher level.

Regulated pressure or atmosphere may be admitted to the several bellows 34, 35 and 36 selectively or in combination. To those 85 skilled in the art, it will be readily understood that several well defined grades of playing intensity may thereby be established.

Upon admitting atmosphere to all the bellows 34, 35 and 36 the forces acting upward upon the valve 31 will so far predominate as to open the valve to enlarge communication between the chests 12 and 14 to the maximum.

Any suitable means may be adopted to govern that part of the regulating mechanism which operates through bellows 34, 35 and 36 to initiate different substantially distinct grades of regulated tension. Herein 100 the duct 40 connects the bellows 34 with a valve chamber 50 having a port to atmosphere and a port to a chamber 60 which is connected to the regulated pressure chest 12 through a passage 61. A duplex valve 51 is 105 mounted in valve chamber 50 and is controlled by a diaphragm 52 of a diaphragm chamber 53. A duct 54 leads from said diaphragm chamber to a vent in the tracker T, correspondingly numbered. The parts 110 50-55 described in connection with duct 40 are triplicated for ducts 41 and 42, the corresponding parts of the valve mechanism for the latter being indicated by the numerals 50, 51, etc., with indices "a" for the valve 115 mechanism for duct 41, and "b" for the valve mechanism for valve 42.

The manner in which the valves 51, 51^a and 51^b may be controlled from the tracker will be sufficiently obvious to those skilled in 120 the art so that a detailed description is unnecessary. Suffice it to say that when any one of the tracker vents is open to atmosphere the bellows corresponding thereto will also be opened to atmosphere, and when a 125 tracker vent is closed to atmosphere its corresponding bellows will be opened to regulated exhaust.

The preceding description has been devoted to an illustrative form of apparatus by 130

which substantially distinct grades or degrees of regulated exhaust may be established for playing notes at substantially distinct grades of intensity. In an apparatus of the 5 character described, it is preferable that the upward pull on the board 33 be maintained substantially uniform. For this purpose the preferred embodiment of the apparatus utilizes a pneumatic system, about to be described, which exerts a pneumatic pull through the bellows 37 in opposition to the bellows 34, 35 and 36; said pneumatic pull being maintained substantially uniform and corrected when necessary. For convenience 10 in that part of the description immediately following, the capacity of the apparatus to produce incremental changes in playing intensities may be disregarded and it may be assumed that regulated exhaust is present in all the bellows 34, 35 and 36 with the result of a maximum downward pressure on the board 33 in the valve 31.

The bellows 37 is connected by a duct 100 with a pneumatic 101, a spring 102 is fastened to the movable board of pneumatic 101 and to an adjustable screw 103 threaded in a block 104. A stop 105 is provided to limit the expanding movement of the pneumatic 101.

30 The pneumatic 101 may be exhausted through a duct 106 opening to a valve chamber 107 having a port 109 to atmosphere and a port 110 to an exhaust chamber 111, preferably connected to high exhaust. A valve 35 112 is mounted in chamber 107 and is controlled by a diaphragm 113 of a diaphragm chamber 114. Diaphragm chamber 114 may be exhausted through a bleed 115 and atmosphere may be admitted thereto through 40 a duct 116 and port 117. The opening of the port 117 is controlled by a valve 118 and as will be readily understood the effective opening of this port relatively to the size of the exhaust bleed 115 will control the operation 45 of the diaphragm 113 and the valve 112, which in turn controls the degree of exhaust in pneumatic 101 and bellows 37.

Communication between pneumatic 101 and valve chamber 107 through duct 106 is 50 somewhat restricted by an adjustable screw 119 which slightly retards the action of the valve 112 upon the pneumatic 101. Upon a slight fluctuation in the degree of exhaust in pneumatic 101 the valve 112 is automatically 55 operated, as hereinafter described, to restore thereby in effect maintaining the degree of exhaust the same substantially uniform. This restoration will be slightly retarded and rendered more delicate and refined because of the interposition of the obstruction 60 119.

For the purpose of more rapidly restoring the intended normal pneumatic condition of pneumatic 101, a second adjustable obstruction 65 screw 120 is likewise interposed between

the valve chamber 107 and the pneumatic 101 and a by-pass around the screw 119 is provided by passages 121 and 122. When it is desired to compensate for an extreme fluctuation in the pneumatic condition 70 of pneumatic 101, the by-pass 121-122 may be opened. By-pass duct 121-122 may be closed by a valve 123 mounted upon a diaphragm of a diaphragm chamber 124. This chamber is connected by a duct 125 with a valve chamber 126 having a port 127 to atmosphere and a port 128 to exhaust chamber 111. A valve 129 controls ports 127 and 128. Normally valve 129 is seated to close exhaust port 128 and open atmosphere port 127 thereby admitting atmosphere to duct 125 and diaphragm chamber 124. This permits valve 123 to be normally seated to close by-pass 121. Upon an extreme fluctuation of the pneumatic condition 85 in the pneumatic 101, the valve 129 is automatically lifted to exhaust diaphragm chamber 124 and open by-pass 121-122, thus permitting a more rapid flow of air along duct 106.

The valve 129 is governed by diaphragm 130 of a diaphragm chamber 131 which communicates by a duct 132 with a port 133 adjacent the port 117, the port 133 being controlled by the valve 118. The usual exhaust 95 bleed for diaphragm chamber 131 is provided by a bleed passage 134.

The valve 118 is operated by an arm 137 projecting from the movable board of the pneumatic 101 and is so arranged that the 100 port 117 will be first opened to operate valve 112 and thereby correct a variation in the pneumatic condition of pneumatic 101. Only thereafter if the expansion of the pneumatic 101 is sufficiently great, will port 133 be 105 opened to cause a more rapid correction of the intended normal pneumatic condition.

The pneumatic 101 is controlled by the differential between the pull of the spring 102 and the action of the exhaust within 110 the pneumatic. With the described arrangement of valves, these opposed forces tend to hold the pneumatic 101 in balance. For example, the pneumatic tends to collapse to that point at which the atmosphere bleed 115 117 is maintained at such a capacity that the degree of exhaust in the diaphragm chamber 114 holds the valve 112 in that position in which the relative exhaust and admission of atmosphere past the valve 112 determines 120 a degree of exhaust within the pneumatic 101 which just balances the pull of the spring 102. Any influence tending to disturb this condition of balance will be promptly compensated so that the ultimate 125 effect is to maintain within the regulator tension system a substantially uniform degree of exhaust which, as will appear to those skilled in the art, will be determined ultimately by whatever tension may be given 130

to the spring 102 by its original adjustment. The mechanism which intervenes between said spring and the regulating pneumatics effectually eliminates the objections to the use of a mechanical spring and serves to transmit the action of said spring in such a way as to refine the regulation and render it extremely accurate. Furthermore, it is preferred that the effective area of the pneumatic 101 be somewhat greater than that of bellows 37 so that the expanding and collapsing movements of the pneumatic 101 (in response to similar movements of the bellows 37) are much less in extent. With such an arrangement the minimized movements of the pneumatic 101 produce only slight elongations and contractions of the spring 102, and therefore produce only minimum changes in the tension of the spring.

That part of the apparatus just described, in addition to its capacity for maintaining substantial uniformity of tension upon the regulator pneumatic, (herein exemplified by bellows 34, 35 and 36) also possesses the capacity of varying playing intensities by varying the upward pull on the regulator and of controlling this variation at different speeds.

If the pneumatic 101 is collapsed beyond its position of normal self-adjustment the spring 102 will be elongated, thereby increasing its tension and causing an accompanying increase in tension of the air condition in pneumatic 101 and bellows 37. This will result if the valve 112 is raised and held in raised position for a substantial length of time, that is, until the pneumatic 101 is completely collapsed. Air will be withdrawn from pneumatic 101 through the small opening formed by the obstruction screw 119 and the increase in tension will therefore take place at a relatively slow speed.

This operation of the pneumatic 101 ultimately causes a slow increase on the upward pull of the movable board 33 and such a variation of one of the forces controlling the valve 31 causes a slow continuously progressive increase in playing intensities. If the valve 112 is lowered to close port 110 and open port 109, atmosphere will be admitted to pneumatic 101 past obstruction screw 119 and permit a slow restoration of the pneumatic 101 to its normal position. This operation, slowly decreases the upward pull on the board 33 with the ultimate result of a slow continuously progressive decrease in playing intensities.

If the valve 129 is raised simultaneously with valve 112 the pneumatic 101 will be collapsed at a greater speed, due to the opening of the by-pass 121-122. If thereafter valve 112 is lowered and valve 129 held in raised position pneumatic 101 will quickly expand. These two operations result respec-

tively in a fast, continuously progressive increase or decrease in playing intensities.

Such changes in playing intensities as are described in the preceding paragraphs are commonly termed crescendo and diminuendo effects.

The above described operations of the valve 112 and 129 for producing crescendos and diminuendos may be controlled by any practicable means. For illustration the diaphragm chamber 114 may be connected to the tracker by a duct 138 opening to a tracker vent correspondingly numbered which may be opened or closed by perforations in a music sheet. The diaphragm chamber 131 may be similarly connected to the tracker bar by a duct 139. As will be readily understood by those skilled in the art the regulating mechanism may thus automatically produce crescendos and diminuendos at different speeds under the control of the note sheet.

The manner of properly coordinating the operations of the several parts of the regulating mechanism under the control of a perforated music sheet will be sufficiently obvious to those skilled in the art and need not be described in detail herein.

The parts of the apparatus acting through the bellows board 33 and having the three-fold capacity for automatically producing incremental changes in playing intensities, for regulating playing intensities, and for automatically producing continuously progressive changes in playing intensities, having been sufficiently described, the means by which the extent of intensity variations may be increased or the average level of playing intensities may be raised, will now be described.

In view of the fact that the conditions surrounding the use of an automatic player piano vary greatly with every instrument, it is difficult in their manufacture to give the parts such primary adjustment as will produce the most satisfactory effects. This fact, in connection with the varying tastes of different piano users, makes it extremely desirable to have associated with the apparatus for automatically obtaining expression variations, additional means to control or vary from time to time the extent of expression changes; specifically to increase the average level of playing intensity. It is often desirable to raise the average level of playing intensities to impart a slightly higher intensity to the notes which would normally be played at points in the lower portion of the scale of intensity of which the instrument is capable. In other words under certain circumstances which can not be readily anticipated in the primary adjustment of the instrument it is often desirable to increase the playing intensities generally without destroying the delicacy of adjustment and re-

finement of operation inherent in the mechanism or the effects produced by the relative character of the changes from one intensity to another.

5 The operation of the instrument in certain respects might of course be controlled by varying the expression mechanism actuating perforations in the note sheet; but obviously it is impracticable to do so because such a 10 course would necessitate specially designed note sheets for each individual instrument. It is desirable to have the means for varying the range of expression changes, capable of operation to produce different effects in 15 the ultimate playing of the instrument at different times and under different circumstances from the same combination of note sheet perforations. In order that the continuity of expression variations and the relative 20 character of the expression changes may not be materially disturbed it is desirable that the means now referred to operate to effect substantially all expression changes proportionately, thereby preserving continuity 25 in the automatic expression governing mechanism. That part of the present invention presently to be described places the operation of the instrument under the control of the user substantially in the manner suggested above.

That part of the apparatus about to be described may also operate to vary the several increments of intensity change predetermined by that part of the expression 30 governing mechanism acting through bellows 34, 35 and 36. It may also operate to modify crescendo effects by increasing the loudness of playing at substantially every point in the crescendo thereby shortening 35 the period of the crescendo. Diminuendo effects may be similarly modified.

In the specific embodiment of the invention disclosed in the drawings, means are provided to cooperate with the previously 40 described bellows apparatus controlling valve 31 and to supplement the forces tending to open port 30 thereby increasing playing intensities. The regulator valve stem 32 is herein extended downwardly 45 through the regulated exhaust chest and carries an adjustable button 250. A bellows 50 is suitably mounted upon some stationary part of the instrument and fast to its movable board 252 is an arm 253 adapted 55 to bear against the button 250 as the bellows 251 is collapsed. A light spring 254, whose functions will be later referred to in more detail, tends to hold the bellows in expanded position.

60 The pneumatic 251 is connected through a valve 255 with a source of exhaust, preferably regulated exhaust in wind chest 12. A duct 256 leads from the interior of the bellows to the valve and a duct 257 leads 65 from the wind chest 12 to the valve. Means

may be provided for varying operative connection between these two ducts and the same will be later referred to, but for the present it may be assumed that the ducts 256 and 257 are directly connected whenever the bellows 251 is brought into operation. 70

The bellows 251, when subjected to exhaust pressure, will exert an upward thrust through the arm 253 upon the valve stem 75 32; the power of the thrust depending upon the area of the bellows, the leverage of the arm and tension of the spring 254. The spring 254 is preferably so adjusted that it will have a slight though constant effect 80 throughout the operation of the bellows 251 and will have a predominating effect in controlling the operation of the bellows 251 when playing intensities are at or approaching the lowest point. 85

It will be apparent to those skilled in the art that the bellows 251 will, when subjected to exhaust pressure, contribute a factor in the balancing equation controlling the operation of the regulator valve 31. 90

It is convenient at this point to summarize the factors heretofore mentioned which normally appear in this balancing equation, which determines the operation of the regulator valve, thereby governing playing intensities. The upward acting forces tending to open the regulator valve and increase playing intensities are (1) the differential between atmospheric pressure on the underside of bellows board 33 and exhaust pressure within bellows 37, (2) the differential between high exhaust in chest 14 and regulated exhaust in chest 12 acting upon the regulator valve 31. The downward acting force tending to close the regulator valve 105 and thereby decrease playing intensities is (1) the differential between atmospheric pressure on the upper side of bellows board 33 and regulated exhaust pressure within any one or all of the bellows 34, 35 and 36. 110

The bellows 251 when in operation adds to the above upwardly acting forces tending to open valve 31 by the differential between atmospheric pressure on the outer surface of the movable board 252 and regulated exhaust within bellows 251 minus the pull of the spring 254. 115

It will be convenient in the following description to regard a force which is the resultant of the differential between atmospheric pressure and exhaust pressure as a positive pull by the air under tension, so-called, the high exhaust or regulated exhaust. So regarding the several forces will be readily understood by those skilled in the art and will simplify the following discussion. It will also be convenient to regard the operation of the step change mechanism as dependent solely upon a change in area of the regulator rather than a change in 120 125 130

area combined with a change in leverage on the bellows board 33.

Omitting the bellows 251, or in other words assuming that the ducts 256 and 257 are not connected the normal balancing equation will be as follows: The upward pull of exhaust within the pouch 37, plus the area of the regulator valve 31 times the difference between high exhaust and regulated exhaust, will equal the regulated exhaust times the acting area of the regulator. Connecting the bellows 251 with the chest 12 will establish a new balancing equation as follows: The upward pull of exhaust within pouch 37, plus the area of the valve 31 times the difference between high exhaust and the newly established regulated exhaust, plus the effective area of bellows 251 times the newly established regulated exhaust, minus the effective power of the spring 254, will equal and balance the newly established regulated exhaust times the acting area of the regulator. In the specific apparatus disclosed the foregoing equation will explain the operation thereof within limits established by the capacity of the instrument. Obviously, a re-arrangement of parts may result in a change in the foregoing equations and it will be understood that they are herein given merely to illustrate a single specific embodiment of the invention.

For convenience of description and explanation of the invention it may be assumed that the playing intensities determinable by the crescendo, diminuendo and the incremental or step change mechanism can be measured on an imaginary scale upon which numeral 4 will indicate the lowest playing intensity while numeral 20 will indicate the loudest playing intensity. Therefore the incremental, crescendo and diminuendo changes will be effected within the compass of this scale from 4 to 20. If the apparatus is adjusted for seven defined grades of playing intensity, as might be the case with the present apparatus, these incremental changes may be assumed to establish playing intensities respectively at 4, 4.5, 5.5, 7.5, 11, 18 and 20 in the imaginary scale. It may further be assumed that a crescendo may be inaugurated when the playing intensity is fixed at any one of the seven points in the scale, except the last, and will in operation, if continued long enough, raise playing intensities, at a greater or less speed as may be determined by the apparatus, from the point at which it is inaugurated to the highest intensity.

Thereafter a diminuendo operation may be inaugurated and decrease playing intensities to any point determined by the step change mechanism.

It may also be assumed that playing intensities vary directly with a variation in

the degree of regulated exhaust so that as playing intensities vary from 4 to 20 regulated exhaust will also vary from 4 to 20 and further that if regulated exhaust is at 11, playing intensities will also be at 11.

Assuming that the expression mechanism heretofore described is set to fix playing intensities at 11 in the supposed scale, and disregarding for the moment the capacity of the apparatus for varying playing intensities from that point, let it be understood that it is desired to increase playing intensity 11 to a point approximating the full power of the instrument and that for this purpose the bellows 251 is connected with the regulated exhaust chest 12. By thus throwing into operation the bellows 251 the forces tending to open valve 31 and increase playing intensities will be increased by the pull of regulated exhaust upon bellows board 252. This pull of regulated exhaust will be opposed by the spring 254 but the spring is preferably so adjusted that at this point it will be overbalanced and the pneumatic will tend to collapse. This tendency to collapse may raise the valve 31 slightly if conditions require a uniform draft upon regulated exhaust. Thus raising the valve 31 subjects regulated exhaust to the influence of high exhaust to a greater extent and increases the degree of regulated exhaust. This increase in regulated exhaust being communicated to the bellows 251 further increases the upward thrust upon the valve 31. Simultaneously with the increase of the upward thrust of bellows 251 there will occur an increase in the downward pull of regulated exhaust upon bellows board 33 due to the increase in the degree of regulated exhaust acting thereon. If under these circumstances the effective area of the movable board of the regulator is greater than the effective area of bellows board 252 a balance will soon be reached wherein the increased downward acting force will balance the increased upward acting force. Areas may be so proportioned that the new balance will be reached when the degree of regulated exhaust approaches 20 in the supposed scale. It will thus be observed that through the agency of the bellows 251 the degree of exhaust normally determined at 11, that is, the crescendo produced by the apparatus when bellows 251 is inactive by the expression mechanism actuating perforations of the note sheet may be raised to 20 by the operation of the bellows 251.

The degree of regulated exhaust and playing intensities having been raised in the above manner they will be maintained uniform at this point in spite of uneven drafts upon regulated exhaust due to the playing of varying numbers of notes concurrently in substantially the same manner as heretofore

described in connection with the maintenance of uniformity of playing by the main expression governing mechanism. If for any reason there is an influx of atmosphere 5 to chest 12 tending to reduce the degree of regulated exhaust, the downward pull upon the bellows board 33 will be relaxed tending to permit the valve 31 to open. But simultaneously the upward thrust of bellows 10 251 will also be relaxed. However, the connection between the arm 253 and the valve stem 32 being such that the bellows 251 in expanding merely causes its arm to fall away from the button 250 the uniformity of 15 playing will be substantially maintained by the main expression governing mechanism. Upon the restoration of the predetermined degree of exhaust in chest 12 the forces in the balancing equation will resume their 20 former values to maintain playing intensities at the predetermined level.

It is preferable that the lowest playing intensity determinable by the main expression governing mechanism be unaffected by 25 the operation of the bellows 251. Assume that the expression mechanism actuating perforations are set to determine playing intensities at 4, the minimum in the supposed scale, under these circumstances the operation 30 of the bellows 251 would tend to increase the upward acting forces operating upon the regulator valve by an amount equal to the pressure of regulated exhaust times the effective area of the bellows board 35 252. If therefore, the spring 254 is so adjusted that it will now balance the force tending to collapse bellows 251 there will be no upward thrust and the balancing equation controlling valve 31 will not be disturbed. This is the preferable arrangement 40 and the parts may be primarily adjusted to this end.

Upon the increase of regulated exhaust determined by the note sheet which would 45 normally raise playing intensities to 4.5 in the supposed scale the increased upward thrust of bellows 251 will overcome the power of the spring and the resultant will be an upward thrust upon the valve 31 50 which will enter into and constitute a factor in the balancing equation controlling the regulator valve. At this intensity the acting area of the movable board of the regulator is relatively large and the slight increase 55 in regulated exhaust acting upon the effective area of bellows board 252 will soon be balanced by the increase in regulated exhaust acting upon the larger area of the movable board of the regulator. Thus the 60 playing intensities will be increased only slightly. As the playing intensities are normally raised step by step in the supposed scale the bellows 251 will have an increasing influence in the balancing equation until, as

previously described, at intensity 11 it will 65 increase playing intensities to intensity 20, which approximates the full power of the instrument.

With the proper primary adjustments and relative proportionment of areas exposed to regulated exhaust the normal scale may be varied as follows: Intensity number 1 may remain at 4. Intensity number 2 may be increased from 4.5 to 4.6; number 3 from 5.5 to 6.1; number 4 from 7.5 to 9.6; 75 number 5 from 11 to 20; number 6 from 18 to the full power of the instrument which is supposed to be 20, and obviously number 7, being the full power of the instrument cannot be further increased. 80

Heretofore the step changes in playing intensities obtained by what in effect is a variation in the area of the movable board of the regulator have been considered in their relation to the operation of the bellows 85 251. During that consideration it has been assumed that the upward pull upon the regulator valve due to the presence of exhaust within bellows 37 has remained uniform, and such will be the case with the 90 present apparatus. The bellows 251 will have an effect upon crescendo expression changes which in general character will be similar to the effect produced at a corresponding point in the scale of intensities determinable by the step change mechanism. 95 There may however, be a difference in extent, due to the fact that in a crescendo operation the area of the movable board of the regulator exposed to regulated exhaust is not necessarily varied. For comparison consider the effect upon regulated exhaust at the point 11 in a crescendo and the corresponding effect at the point 11 determined by the step change mechanism. 100 As previously noted in order to produce intensity 11 through the agency of the step change mechanism the effective area of the movable board of the regulator bellows is decreased. Thus decreasing the area causes 105 the balance between the upward thrust of bellows 251 and the downward pull of the regulator bellows to be attained when regulated exhaust has been increased substantially to 20. 110

If it is assumed that a crescendo operation has been begun at the lowest intensity (point 4) the entire area of the regulator bellows will then be exposed to regulated exhaust. Therefore the difference between 115 the regulator bellows area and the area of bellows 251 is greater and the balance will be reached somewhat sooner or, with the same assumed values at substantially 120 13. From this point on the bellows 251 will have an increasing effect in the balancing equation and will cause the high point of the crescendo to be reached sooner than it 125

otherwise would without bellows 251 in operation. Therefore the bellows 251 will have an increasing effect upon the crescendo as it raises playing intensities gradually 5 from 4 to 20.

For further illustration it may be assumed that a crescendo operation has been inaugurated from the 4th intensity step i. e. point 7.5 in the supposed scale. Under such circumstances the acting area of the regulator bellows may be considerably less than in the foregoing assumed case. Therefore the difference between the regulator bellows area and the area of bellows 251 is less than before 10 and the new balance will not be reached as quickly. This will require a greater increase in regulated exhaust before the balance is reached and with the same assumed values point 11 in the normal crescendo will 15 now become 15.5.

Throughout crescendo operations the lowest possible point of a crescendo that is point 4 in the supposed scale, may not be changed by the introduction of regulated 20 exhaust to bellows 251.

The opposite effect of the bellows 251 during a diminuendo operation will be obvious to those skilled in the art.

It will be seen from the foregoing description that the part of the invention operating 30 through pneumatic 251 embodies convenient means for varying the range of effects which can be produced by the automatic action of the instrument. Such a device is of extreme value in that it permits the instrument to be readily adapted to the surrounding circumstances amid which it is used. Furthermore it permits, what 35 may be termed the contrast in expression to be increased for certain selected compositions or parts of the same composition.

As far as the step change mechanism is concerned it modifies the ultimate effect of expression actuating perforations so that the 40 apparatus produces larger increments of change in intensity from one step to the next without however destroying the delicacy of playing in the lower ranges of intensity. In effect it renders the scale of intensities 45 elastic in that the upper range of intensity change is raised while the lower or normal minimum intensity may not be effected. For illustration, assume a composition wherein the expression is varied between the first 50 four intensities, that is, from 4 to 7.5. With the same note sheet the range of expression changes can be extended through the agency of the pneumatic 251 so that the expression may vary between 4 and 9.6, thus producing 55 greater contrast in the composition. Crescendo and diminuendo changes may be similarly effected without a variation in the note sheet perforations or in adjustment of the main apparatus. A crescendo operation, 60 through the pneumatic 251, will be caused 65

to reach a higher point in a given time than would be the case in the absence of the pneumatic 251.

It has been assumed that the pneumatic 251 may be connected alternatively with a 70 source of exhaust, for instance, the regulated wind chest 12, or with atmosphere; thus rendering the intensifier operative to its full extent or entirely inoperative. Means may however be provided whereby the pneumatic 251 may have a different effect to 75 raise playing intensities by a less amount and such means are herein provided through the agency of the valve 255.

Valve 255 previously referred to, comprises a valve casing 258 having a movable piston 259 which is adapted to slide endwise and may be operated by any convenient means such as a lever 260 mounted preferably upon the key rail of the piano. The 80 movement of the valve piston 259 is limited by a pin 275, which moves in a slot 276 in the valve casing. The ducts 256 and 257 open to the interior of the valve through ports 261 and 262 respectively while a port 90 263 provides for the admission of atmosphere to the interior of the valve. The valve piston is chambered to form a D valve and the valve is preferably so proportioned that the port 261 is always open to the 95 valve chamber while the ports 262 and 263 may be placed in communication with the valve chamber by operating the lever 260. When the port 262 is wide open the port 263 will be closed. This is the position 100 shown in the drawings and such a position of the valve places duct 257 in full communication with duct 256, with the result that playing intensities are increased by the maximum increase attainable through the operation 105 of the bellows 251.

If the valve piston is moved to the left it will gradually close port 262 and open port 263 allowing atmosphere to bleed into the valve and thereby reduce the degree of 110 exhaust in the pneumatic 251 relatively to the degree of exhaust within wind chest 12. This will decrease the upwardly acting force in the bellows 251 which tends to open the regulator valve 31 and will thereby establish 115 a new balancing equation which will so control the apparatus as to increase playing intensities by a less amount than the predetermined maximum increase. As the movement of the valve piston continues 120 toward the left the port 262 will be finally closed and the port 263 will be open, thus the valve effectually cuts off all communication between wind chest 12 and bellows 251 and opens the latter to atmosphere. Admitting atmosphere to bellows 251 renders it entirely inoperative and the playing intensities will be governed solely by the main regulating apparatus acting through bellows board 33. The results obtained by thus de- 125 130

creasing the degree of exhaust in bellows 251 relatively to that in the regulated exhaust chest will be apparent to those skilled in the art from the foregoing description 5 and further explanation is deemed unnecessary.

It should be understood that in the preceding description the scale of intensities from 4 to 20 and the stated increases at any 10 given point in this scale are assumed and arbitrary points selected merely for purposes of illustration, although the lower and upper limits of the scale happen to correspond to the height to which a column of 15 water would be drawn by the regulated exhaust at the lowest and highest playing intensities respectively.

It is to be understood that the principal features of the present invention are not 20 necessarily limited to use in combination with the particular expression governing means herein disclosed but that the same may be variously combined with other means for normally regulating intensities and with 25 means for producing crescendo and diminuendo changes. Furthermore the present invention is not limited to the specific details, construction, organization, and mode of operation hereinbefore described for the 30 purpose of illustration; on the contrary, the invention may be variously modified and embodied within the scope of the subjoined claims.

I claim as my invention:

35 1. An automatic musical instrument comprising, in combination, playing actions; a main source of power for operating said playing actions; a throttle valve between the main source of power and the playing actions; expression governing means operatively connected to said throttle valve to vary the degree of power transmitted from the source to the playing actions; and supplementary expression governing means responsive to variations in and tending to increase the degree of power transmitted to the playing actions as governed by said first named expression governing means.

40 2. An automatic musical instrument comprising, in combination, playing actions; a main source of power for operating said playing actions; a throttle valve between the main source of power and the playing actions; expression governing means operatively connected to said throttle valve to vary the degree of power transmitted from the source to the playing actions; and supplementary variably acting pneumatic means tending to increase the degree of power 45 transmitted to the playing actions as governed by said first named expression governing means.

40 3. An automatic musical instrument comprising, in combination; playing actions; a main source of power for operating said

playing actions; a throttle valve between the main source of power and the playing actions; a regulating pneumatic operatively connected to said throttle valve, having connection with regulated air governed by said 70 throttle valve and tending to close the same; and a supplementary regulating pneumatic also having connection with regulated air operatively connected to and tending to open said valve. 75

4. An automatic musical instrument comprising, in combination, playing actions; a main source of power for operating said playing actions; a throttle valve between the main source of power and the playing 80 actions; expression governing means including a regulating pneumatic operatively connected to said throttle valve and tending to close the same; and supplementary expression governing means having connection with regulated air governed by said 85 throttle valve and tending to open said valve.

5. An automatic musical instrument comprising, in combination, playing actions; a 90 main source of power for operating said playing actions; a throttle valve between the main source of power and the playing actions; a tracker; tracker controlled expression governing means operatively connected to said throttle valve to vary the degree of power transmitted from the source to the playing actions; and supplementary expression governing means responsive to fluctuations in and tending to increase the 100 degree of power transmitted to the playing actions by said tracker controlled expression governing means. 95

6. An automatic musical instrument comprising, in combination, playing actions; a 105 main source of power for operating said playing actions; a throttle valve between the main source of power and the playing actions; a tracker; tracker controlled expression governing means operatively connected to said throttle valve to vary the degree of power transmitted from the source to the playing actions; and supplementary pneumatic means responsive to fluctuations in and tending to increase the degree of 110 power transmitted to the playing actions as governed by said tracker controlled expression governing means.

7. An automatic musical instrument comprising, in combination, playing actions; a 120 main source of power for operating said playing actions; a throttle valve between the main source of power and the playing actions; a tracker; tracker controlled expression governing means including a regulating pneumatic operatively connected to said throttle valve, having connection with regulated air governed by said throttle valve and tending to close the same; and a supplementary regulating pneumatic hav- 125 130

ing connection with regulated air operatively connected to and tending to open said valve.

8. An automatic musical instrument comprising, in combination, playing actions; a main source of power for operating said playing actions; a throttle valve between the main source of power and the playing actions; a tracker; tracker controlled expression governing means including a regulating pneumatic operatively connected to said throttle valve, having connection with regulated air governed by said throttle valve and tending to close the same; a supplementary regulating pneumatic operatively connected to said valve; and means to connect said pneumatic alternatively to regulated air or to atmosphere.

9. An automatic musical instrument comprising, in combination, playing actions; a main source of power for operating said playing actions; a throttle valve between the main source of power and playing actions; expression governing means operatively connected to said valve for inaugurating and maintaining substantially distinct increments of change in playing intensities; and supplementary expression governing means to increase the respective increments of change inaugurated by said last named means.

10. An automatic musical instrument comprising, in combination, playing actions; a main source of power for operating said playing actions; a throttle valve between the main source of power and the playing actions; a tracker; tracker controlled expression governing means for inaugurating and maintaining substantially distinct increments of change in playing intensities; and supplementary expression governing means to increase the respective increments of change inaugurated by said tracker controlled means.

11. An automatic musical instrument comprising, in combination, playing actions; a main source of power for operating said playing actions; a throttle valve between the main source of power and the playing actions; a tracker; tracker controlled expression governing means for inaugurating and maintaining substantially distinct increments of change in playing intensities; and manually controlled means to increase the respective increments of change inaugurated by said tracker controlled means.

12. An automatic musical instrument comprising, in combination, playing actions; a main source of power for operating said playing actions; a throttle valve between the main source of power and the playing actions; pneumatic expression governing means for inaugurating and maintaining substantially distinct increments of

change in playing intensities; and means for progressively varying the increments of change inaugurated by said last named means.

13. An automatic musical instrument comprising, in combination, playing actions; a main source of power for operating said playing actions; a throttle valve between the main source of power and the playing actions; expression governing means for inaugurating and maintaining substantially distinct increments of change in playing intensities; and means for progressively increasing the increments of change so inaugurated by said last named means.

14. An automatic musical instrument comprising, in combination, playing actions; a main source of power for operating said playing actions; a throttle valve between the main source of power and the playing actions; a tracker; tracker controlled expression governing means for inaugurating and maintaining substantially distinct increments of change in playing intensities; and progressively increasing the respective increments of change inaugurated by said tracker controlled means.

15. An automatic musical instrument comprising, in combination, playing actions; a main source of power for operating said playing actions; a throttle valve between the main source of power and the playing actions; a tracker; tracker controlled expression governing means for inaugurating and maintaining substantially distinct increments of change in playing intensities; and manually controlled means for progressively increasing the respective increments of change inaugurated by said tracker controlled means.

16. An automatic musical instrument comprising, in combination, playing actions; a main source of power for operating said playing actions; a throttle valve between the main source of power and the playing actions; expression governing means for increasing playing intensities by distinct increments including a regulating pneumatic operatively connected to said throttle valve and having connection with regulated air governed thereby; and a pneumatic acting upon said throttle valve in opposition to said regulating pneumatic and connected to regulated air for enlarging the incremental changes inaugurated by said expression governing means.

17. An automatic musical instrument comprising, in combination, playing actions; a main source of power for operating said playing actions; a throttle valve between the main source of power and the playing actions; a tracker; tracker controlled expression governing means for increasing playing intensities by distinct increments

- including a regulating pneumatic operatively connected to said throttle valve and having connection with regulated air governed thereby; and a pneumatic acting upon
- 5 said throttle valve in opposition to said regulating pneumatic and connected to regulated air for enlarging the incremental changes inaugurated by said expression governing means.
- 10 18. An automatic musical instrument comprising, in combination, playing actions; a main source of power for operating said playing actions; a throttle valve between the main source of power and the playing actions; a tracker; tracker controlled expression governing means for increasing playing intensities by distinct increments including a regulating pneumatic operatively connected to said throttle valve and having connection with regulated air governed thereby; a pneumatic acting upon said throttle valve in opposition to said regulating pneumatic and connected to regulated air for enlarging the incremental changes inaugurated by said expression governing means; and a manually controlled valve to govern said last named means.
- 15 19. An automatic musical instrument comprising, in combination, playing actions; a main source of power for operating said playing actions; a throttle valve between the main source of power and the playing actions; expression governing means including a regulating device of variable acting area operatively connected to and tending to close said throttle valve; and a pneumatic operatively connected to and tending to open said throttle valve connected with a source of exhaust controlled by said throttle valve.
- 20 20. An automatic musical instrument comprising, in combination, playing actions; a main source of power for operating said playing actions; a throttle valve between the main source of power and the playing actions; expression governing means including a regulating device of variable acting area operatively connected to and tending to close said throttle valve; a pneumatic operatively connected to and tending to open said throttle valve; and means to connect said pneumatic alternatively with atmosphere or with a source of exhaust controlled by said throttle valve.
- 25 21. An automatic musical instrument comprising, in combination, playing actions; a main source of power for operating said playing actions; a throttle valve between the main source of power and the playing actions; expression governing means including a regulating device of variable acting area operatively connected to and tending to close said throttle valve; a tracker; tracker controlled means to vary the acting area of said regulating pneumatic; a pneumatic operatively connected to said throttle valve and
- tending to open same; and means to connect said pneumatic alternatively with atmosphere or with a source of exhaust controlled by said throttle valve.
22. An automatic musical instrument comprising, in combination, playing actions; a main source of power for operating said playing actions; a throttle valve between the main source of power and the playing actions; pneumatic expression governing means for inaugurating and maintaining substantially distinct increments of change in playing intensities; and a pneumatic operatively connected to said throttle valve and to a source of exhaust controlled thereby for progressively increasing the increments of change inaugurated by said last named means.
- 27 23. An automatic musical instrument comprising, in combination, playing actions; a main source of power for operating said playing actions; a throttle valve between the main source of power and the playing actions; a tracker; tracker controlled expression governing means for inaugurating and maintaining substantially distinct increments of change in playing intensities; means for progressively increasing the respective increments of change inaugurated by said tracker controlled means, including a pneumatic operatively connected to said throttle valve and to a source of exhaust controlled thereby for progressively increasing the increments of change inaugurated by said last named means.
- 32 24. An automatic musical instrument comprising, in combination, playing actions; a main source of power for operating said playing actions; a throttle valve between the main source of power and the playing actions; a tracker; tracker controlled expression governing means for inaugurating and maintaining substantially distinct increments of change in playing intensities; a pneumatic operatively connected to said throttle valve for progressively increasing the respective increments of change inaugurated by said tracker controlled means and having connection with regulated exhaust; and a manually controlled valve in said connection.
- 37 25. An automatic musical instrument comprising, in combination, playing actions; a main source of power for operating said playing actions; a throttle valve between the main source of power and the playing actions; expression governing means operatively connected to said throttle valve for varying expression by substantially continuous progression; and supplementary means operatively connected to said valve for varying the speed of the progression.
- 42 26. An automatic musical instrument comprising, in combination, playing actions; a main source of power for operating said

- playing actions; a throttle valve between the main source of power and the playing actions; expression governing means operatively connected to said throttle valve for varying expression by substantially continuous progression; and supplementary pneumatic means operatively connected to said valve for varying the speed of the progression.
- 10 27. An automatic musical instrument comprising, in combination, playing actions; a main source of power for operating said playing actions; a throttle valve between the main source of power and the playing actions; a tracker; tracker controlled means operatively connected to said valve to vary by substantially continuous progression the degree of power transmitted from the source to the playing actions; and means including a pneumatic operatively connected to said valve and having connection with a source of exhaust controlled thereby for increasing the effective speed of operation of said tracker controlled means.
- 15 28. An automatic musical instrument comprising, in combination, playing actions; a main source of power for operating said playing actions; a throttle valve between the main source of power and the playing actions; a tracker; tracker controlled means operatively connected to said valve to vary by substantially continuous progression the degree of power transmitted from the source to the playing actions; a pneumatic operatively connected to said throttle valve and tending to open the same to increase the effective speed of operation of said tracker controlled means; and manually controlled means for alternatively connecting said
- 20 pneumatic to atmosphere or to a source of exhaust controlled by said throttle valve.
- 25 29. An automatic musical instrument comprising, in combination, playing actions; a main source of power for operating said playing actions; a throttle valve between the main source of power and the playing actions; expression governing means operatively connected to and tending to open said throttle valve for crescendo and diminuendo expression changes at predetermined speeds; and supplementary pneumatic means connected to said throttle valve and tending to open same to increase the predetermined speed of the crescendo and diminuendo changes.
- 30 30. An automatic musical instrument comprising, in combination, playing actions; a main source of power for operating said playing actions; a throttle valve between the main source of power and the playing actions; expression governing means including a regulating pneumatic operatively connected to and tending to close said valve; supplementary expression governing means including a pneumatic connected to and tending to open said valve and having connection with a source of exhaust controlled by said valve; and means to diminish the operative effect of said last named means.
- 35 31. An automatic musical instrument comprising, in combination, playing actions; a main source of power for operating said playing actions; a throttle valve between the main source of power and the playing actions; expression governing means including a regulating pneumatic operatively connected to and tending to close said valve for varying playing intensities from a normal minimum to a predetermined maximum; means including a pneumatic acting upon said throttle valve and tending to increase playing intensities so governed; and means to render said last named means ineffective when playing intensities are governed at the normal minimum.
- 40 32. An automatic musical instrument comprising, in combination, playing actions; a main source of power for operating said playing actions; a throttle valve between the main source of power and the playing actions; expression governing means including a regulating pneumatic operatively connected to and tending to close said valve for varying playing intensities from a normal minimum to a predetermined maximum; means including a pneumatic acting upon said throttle valve and tending to increase playing intensities so governed; and a spring acting upon said pneumatic to render said last named means ineffective when playing intensities are governed at the normal minimum.
- 45 33. An automatic musical instrument comprising, in combination, playing actions; a main source of power for operating said playing actions; a throttle valve between the main source of power and the playing actions; expression governing means including a regulating pneumatic operatively connected to and tending to close said valve for varying playing intensities from a normal minimum to a predetermined maximum; and means acting upon said throttle valve to vary playing intensities so governed and being increasingly effective as playing intensities approach the maximum.
- 50 34. An automatic musical instrument comprising, in combination, playing actions; a main source of power for operating said playing actions; a throttle valve between the main source of power and the playing actions; means to maintain uniformity of playing whether one or many notes are simultaneously sounded; means to increase playing intensities from a normal minimum to a predetermined maximum; and supplementary means to vary the increase in playing intensities as inaugurated by said last

named means by a progressively increasing proportion from the normal minimum to the predetermined maximum.

35. An automatic musical instrument comprising, in combination, playing actions; a main source of power for operating said playing actions; a throttle valve between the main source of power and the playing actions; means to maintain uniformity of playing whether one or many notes are simultaneously sounded; means to decrease the playing intensities from a predetermined maximum to a normal minimum; and supplementary means to vary the decrease in playing intensities as inaugurated by said last named means by a progressively decreasing proportion from the predetermined maximum to the normal minimum.

36. An automatic musical instrument comprising, in combination, playing actions; a main source of power for operating said playing actions; a throttle valve between the main source of power and playing actions;

expression governing means for varying playing intensities by distinct increments; 25 and supplementary expression governing means for varying said incremental changes by a proportion progressively increasing with each incremental change.

37. An automatic musical instrument comprising, in combination, playing actions; a main source of power for operating said playing actions; a throttle valve between the main source of power and playing actions; expression governing means for varying 35 playing intensities by substantially continuous progression; and supplementary expression governing means modifying the action of said last named means by a proportion progressively increasing with the increase in 40 playing intensities.

In testimony whereof, I have signed my name to this specification this 23rd day of November, 1917.

CHARLES F. STODDARD.

Certificate of Correction.

It is hereby certified that in Letters Patent No. 1,409,496, granted March 14, 1922, upon the application of Charles F. Stoddard, of New York, N. Y., for an improvement in "Automatic Musical Instruments," an error appears in the printed specification requiring correction as follows: Page 6, lines 117 and 118, strike out the comma and phrase "that is, the crescendo produced by the apparatus when bellows 251 is inactive" and insert the same to follow the word "crescendo," line 19, page 8; and that the said Letters Patent should be read with this correction therein that the same may conform to the record of the case in the Patent Office.

Signed and sealed this 13th day of June, A. D., 1922.

[SEAL.]

KARL FENNING,

Acting Commissioner of Patents.
